UNITED STATES PATENT OFFICE

FRANK DI IANNI, OF BROOKLYN, NEW YORK, ASSIGNOR TO AMERICAN MACHINE & FOUNDRY COMPANY, A CORPORATION OF NEW JERSEY

PAPER PULL FOR CIGARETTE MACHINES

Application filed April 4, 1928. Serial No. 267,447.

This invention relates to a paper pull for cigarette machines, its main object being to pull the paper through the rod-forming mechanism of the machine when the latter is started, after a new paper reel has been inserted or a new paper end has been fed through the forming mechanism after a break of the paper, the pull being continued until the rod has acquired sufficient strength 10 to automatically break and jump the gap to the cutoff mechanism.

In the operation of continuous rod cigarette machines heretofore, the leading end of the paper or wrapper-strip has been pulled 15 through the rod-forming mechanism by hand. Immediately after the machine is started, the rod is soft because there is insufficient tobacco encased in the wrapper to give it proper density. Moreover, pulling 20 the wrapper-strip through the forming mechanism by hand, does not give it the same speed as that of the rod-forming tape, so that the irregularity of pull frequency results in wastage of the paper and tobacco 25 filler therefor.

The present device overcomes this difficulty and generally speaking consists of a roller which is pressed against the tape-wheel of the machine by a spring, the tape-wheel 30 driving the forming tape which guides the wrapper through the rod-forming mechanism of the machine. The leading end of the wrapper-strip, after having been led by hand through the printer, past the tobacco feed, 35 the rod-forming mechanism, the paster and the sealer, is clamped against the tape-wheel by the roller, and is thus pulled through the machine at the same speed as the tape, after the machine is started. When the portion of 40 the wrapper-strip which is completely filled with tobacco and formed into a rod of the proper strength, arrives at the tape-wheel and under the paper pulling roller, the curvature of the wheel causes the rod to break, 45 whereupon the free end of the same, which is held straight by its own stiffness, automatically jumps the gap into the bell-mouth of the cutoff mechanism. The paper puller, no longer required, is thrown out of engagement 50 with the tape-wheel and held in inoperative

position during normal operation of the machine.

The invention consists in certain constructions and combinations which will be hereinafter fully described and then specifically set forth in the claims hereunto appended.

In the accompanying drawings, in which like characters of reference indicate the same or like parts; Fig. 1 is a plan view of a device constructed in accordance with the invention; Fig. 2 is a side elevation of the device shown in Fig. 1, showing the newly formed cigarette rod being pulled over the tape-wheel at the moment, when having reached its proper strength, it automatically breaks and jumps the gap to the cutoff; Fig. 3 is a front elevation of a part of the tape-wheel and the roller showing the empty paper being pulled over the wheel by the action of the roller; and Fig. 4 is a front elevation of a part of the tape-wheel showing the free end of the formed cigarette rod jumping the gap to the bell-mouth of the cutoff, after having been broken off as shown in "B" in Fig. 2.

In carrying the invention into effect, there is provided the rod-forming mechanism of a cigarette machine and the means coacting therewith to pull the wrapper-strip through said mechanism until the cigarette rod acquires sufficient strength to break the strip and jump the gap to the cutoff. In the best constructions contemplated, there is also provided means for holding the pulling means out of action during normal operation of the machine, and the pulling means coacts with the tape-driving wheel of the rod-forming mechanism of the cigarette machine. The parts above mentioned may be varied in construction within the scope of the claims, for the specific device selected to illustrate the invention is but one of numerous concrete embodiments of the same. The invention, therefore, is not to be restricted to the precise details of the specific structure shown and described.

Referring to Figs. 1 and 2, P indicates the end of a newly started wrapper-strip which has been manually led through the printer, the tobacco feed, the rod former, the paster

and the rod sealer, and has finally been led over the tape-wheel 5 which drives the endless rod-forming tape 6, upon which the paper P rests as it comes from the tobacco feed of the machine. The tape 6 runs in the customary manner over a number of idlers 7, of which only one is shown. Shaft 8 carrying the wheel 5 and the studs 9 of the idler 7 are carried by the frame 10 of the cigarette machine in the usual manner. The tape 6 is supported by the plate 11, attached by a bracket 12 to the frame 10 as usual.

After the paper P has been led over the tape-wheel 5, it is pressed against the same by a rubber covered roller 13, which is mounted by means of a stud 14 on a movable arm 15, which swings on a stud 16 held in a bracket 17 carried by the frame 10. A torsion spring 18 connects the arm 15 with the projecting lug 17' of the bracket 17 and normally holds the roller 13 against the tape-wheel 5.

When the machine is now set into operation, the rotation of the wheel 5 pulls the paper through the machine as shown in Fig. 3, the paper being filled as it passes under the tobacco feed, not shown, and formed into a cigarette C, as it travels through the rod-forming mechanism of the machine. As the finished rod C emerges from the well known sealer 19, which is turnable on a pintle 20 by a handle 21, and when in operation presses rod C against the plate 11, the strength of the rod causes it to break as shown in B in Fig. 2. The free end of rod C, which is now driven by the pressure of the tape 6 in the rod-forming mechanism, then jumps the gap and enters the bell-mouth 22 of the cutoff mechanism as shown in Fig. 4. The bell-mouth 22 is connected by an arm 23 with a cutoff mechanism which divides the rod C into individual cigarettes.

The cigarette rod now being driven without the aid of the roller 13, the latter is moved into the inoperative position shown by dotted lines in Fig. 2, in which a slot 25 in the hub of the arm 15 registers with a pin 26 of the stud 16 and is pushed into engagement with it by a spring 27 in the hub of the arm 15.

To again put the roller 13 into action, the arm 15 is pulled outwardly until the slot 25 is disengaged from the pin 26. The torsion spring 18 will then force the roller against the wrapper-strip on the wheel 5.

The new device, besides pulling the empty and partly filled paper downward over the tape-wheel, thereby preventing its accumulation before the cutoff, thus also performs the function of automatically breaking the rod at the proper moment to permit it to jump the gap to the cutoff, and this results in a material saving of paper and tobacco every time the machine is started after shutdown for paper breakage or other reason.

What is claimed is:

1. The combination with the rod-forming mechanism of a cigarette machine spaced from the cutoff to provide a gap, of means coacting therewith to pull a wrapper-strip through said mechanism until the cigarette rod acquires sufficient strength to break the strip and jump the gap to the cutoff. 70

2. The combination with the rod-forming mechanism of a cigarette machine spaced from the cutoff to provide a gap, of means coacting therewith to pull a wrapper-strip through said mechanism until the cigarette rod acquires sufficient strength to break the strip and jump the gap to the cutoff, and means for holding the pulley means out of action during normal operation of the machine. 75

3. The combination with the tape-driving wheel of the rod-forming mechanism of a cigarette machine spaced from the cutoff to provide a gap, of means coacting therewith to pull a wrapper-strip through said mechanism until the cigarette rod acquires sufficient strength to break the strip and jump the gap to the cutoff. 80

4. The combination with the tape-driving wheel of the rod-forming mechanism of a cigarette machine spaced from the cutoff to provide a gap, of a spring-pressed roller coacting therewith to pull a wrapper-strip through said mechanism until the cigarette rod acquires sufficient strength to break the strip and jump the gap to the cutoff. 85

5. The combination with the tape-driving wheel of the rod-forming mechanism of a cigarette machine spaced from the cutoff to provide a gap, of a spring-pressed roller coacting therewith to pull a wrapper-strip through said mechanism until the cigarette rod acquires sufficient strength to break the strip and jump the gap to the cutoff, an arm supporting said roller, and means for holding said arm and roller out of action during normal operation of the machine. 90

6. The combination with the tape-driving wheel of the rod-forming mechanism of a cigarette machine spaced from the cutoff to provide a gap, of a roller coacting therewith to pull a wrapper-strip through said mechanism until the cigarette rod acquires sufficient strength to break the strip and jump the gap to the cutoff, an arm supporting said roller, a torsion spring acting to cause said arm to press said roller against said wheel, and a spring catch for holding said arm and roller out of action during normal operation of the machine. 110

In testimony whereof, I have signed my name to this specification.

FRANK DI IANNI.
